UNITED STATES PATENT OFFICE

SOL S. LEAF, OF CHICAGO, ILLINOIS, ASSIGNOR TO OVERLAND CANDY CORPORATION, OF CHICAGO, ILLINOIS, A CORPORATION OF ILLINOIS

DESIGN FOR AN ICE CREAM SANDWICH WAFER

Application filed July 17, 1931. Serial No. 40,578. Term of patent 14 years.

To all whom it may concern:

Be it known that I, Sol S. Leaf, a citizen of the United States, residing at Chicago, in the county of Cook and State of Illinois, have invented a new, original, and ornamental Design for Ice Cream Sandwich Wafers, of which the following is a specification, reference being had to the accompanying drawings, forming part thereof.

Fig. 1 is a side elevation of an ice cream sandwich wafer showing my new design.

Fig. 2 is a plan view of the bottom of the sandwich wafer.

Fig. 3 is a plan view of the inside of the ice cream sandwich wafer.

I claim:

The ornamental design for an ice cream sandwich wafer as shown.

In witness whereof, I hereunto subscribe my name, this 15th day of July, 1931.

SOL S. LEAF.
